UNITED STATES PATENT OFFICE.

WILLIAM H. SPENCER, OF LEWISTON, MAINE, ASSIGNOR TO TEXTILE MACHINE COMPANY, OF LEWISTON, MAINE, A CORPORATION.

LOOM FEELER AND HOLDER THEREFOR.

Application filed April 5, 1926. Serial No. 99,921.

The invention relates to improvements in automatic looms provided with feelers or detectors which engage the shuttle fillings and automatically effect doffing of a substantially empty bobbin, and insertion of a new filling from the magazine. The invention relates primarily to feelers of the type used on the Crompton and Knowles automatic loom, in which the feeler comprises a spring-projected slide mounted in a feeler case and provided with a fixed feeler point and a pivotally mounted detector or swiper. Each time the filling is engaged with a feeler, it comes in contact both with the feeler point and the swiper, and the latter is intended to be held against movement by engagement with the filling. Under certain well known conditions however, this swiper very often moves prematurely and causes doffing of a filling which is by no means exhausted, whereas movement of said swiper is only intended to take place when the filling has become so exhausted that the feeler point may contact directly with the bobbin.

It is the object of my invention to provide an exceptionally simple, inexpensive and efficient improvement in a feeler of the type set forth which will engage the filling and virtually lock the swiper against bobbin-doffing movement until the filling has been exhausted to such an extent as to make it essential that a new filling be substituted. The use of my invention also permits the loosening of the feeler-projecting spring, so that the feeler does not engage the filling with as much force as heretofore, there being consequently less danger of injuring said filling.

With the foregoing in view, the invention resides in the novel subject matter herein-after described and claimed, the description being supplemented by the accompanying drawing.

Fig. 1 is a horizontal sectional view through the upper portion of the feeler case, showing the feeler in top plan view and illustrating my improvement applied to the swiper and feeler point.

Fig. 2 is an enlarged horizontal section through the front portion of the feeler and associated parts, showing the normal relation of such parts when the feeler is engaged by the filling.

Fig. 3 is a view similar to Fig. 2 but illustrating the manner in which the movement

of the swiper is permitted when the feeler point directly engages the bobbin.

Fig. 4 is a transverse sectional view as indicated by line 4-4 of Fig. 2.

In the drawing above briefly described, 60 the numeral 5 designates an ordinary feeler case and 6 designates the slideable feeler mounted in said case for rearward movement against the action of the usual spring 7 each time the shuttle filling 8 is engaged with the 65 feeler, by movement of the lay toward the breast beam.

The front end of the feeler slide 6 is provided with the usual feeler point 9, and the well known swiper or movable detector 10 70 is provided at one side of said feeler point, this swiper being adjustably pivoted at 11 to the slide 6 and having the usual toothed end 2 for engagement with the filling 8, this end being spaced slightly in rear of the outer 75 extremity of the feeler point 9, so that when the latter engages the bobbin 13 as indicated in Fig. 3, the swiper 10 is free to swing outwardly as shown in this view, thus effecting movement of the usual push rods 14 and 15, 80 to bring the filling-doffing means and the magazine into play so as to automatically discharge an empty filling and insert a new one from the magazine.

Very often, under certain well known conditions, the swiper 10 will swing outwardly to the position of Fig. 3, before the bobbin 13 is anywhere near exposed by the filling 8, this being due to slippage of the swiper upon the filling. Such an occurrence causes 90 premature doffing of the filling and insertion of another, with obvious and well known disadvantages. Due to the nature of my invention however, such an occurrence cannot take place.

I provide a lateral extension 16 for the swiper 10, said extension being preferably in the form of an arm pivoted at 17 to said swiper. This extension or arm extends transversely of the feeler point 9 to the side 100 of the latter remote from the swiper 10 and is provided at its free end with a shoe 18 to engage the filling 8, said shoe preferably having a broad flat face to contact with the filling, so that there is no danger of injuring the latter. In the present showing, the extension or arm 16 passes slidably through a slot 19 in the feeler point 9, but if desired, this feeler point could be provided with some other means for guiding said extension or 110

arm, so that its filling-engaging surface, like the teeth of the swiper end 12, will always be disposed a trivial distance behind the outer terminal of the feeler point.

5 By the construction and arrangement shown, if the swiper 10 has any tendency to creep or slide upon the filling 8, such tendency is resisted by engagement of the extension 16 with said filling, so that the 10 outward swinging of the swiper and consequent change of fillings cannot take place, until the feeler point 9 actually comes in contact with the bobbin 13 as shown in Fig. 3. Moreover, if the swiper does not 15 touch the filling, due to failure of the feeler point to penetrate a conical end portion of the filling sufficiently, the extension 16, being closer to the larger end of the conical portion than the swiper, will engage the 20 same and hold said swiper against outward swinging. Thus, the swiper 10 is virtually locked against premature movement and dosing of one filling and insertion of another, cannot take place until the filling 25 in the bobbin has been exhausted to such an extent as to permit direct contact of the feeler point with the bobbin. Hence, a great deal of trouble and expense now encountered in the operation of automatic 30 looms are effectively overcome, more and better work can be produced, and one attendant may readily look after a greater number of machines. Moreover, due to the 35 combined holding actions of the swiper end 12 and the extension 16, said swiper end need not be held against the filling with as much force as is now required, permitting the spring 7 to be loosened and insuring that no parts of the feeler shall 40 engage the filling with sufficient force to injure the latter, even though it be rayon or some other delicate material.

In the preferred manner of constructing the invention, the inner end of the arm 16 45 is formed with a notch 20. This notch receives an ear 21 which projects from the head 22 of a rivet or the like 23, this fastener being passed through the swiper 10 at a point behind its end 12, and being 50 upset as at 24 or otherwise secured. By this construction, not only can my addition to the ordinary feeler be easily and inexpensively manufactured, but it may be connected with the conventional feeler parts 55 in an easy, rapid and inexpensive manner, it being simply necessary, according to the present disclosure to form an opening through the swiper 10 to receive the fastener 23 and to form the opening 19 through 60 the feeler point 9.

In every day service, the invention is giving excellent results and it has effectively overcome difficulties which were previously considered practically unsurmountable, and as these advantages have been obtained 65 from a device constructed as herein disclosed, the details which I have illustrated are preferably followed. However, within the scope of the invention as claimed, variations may, of course, be made. 70

I claim:

1. In combination with a loom feeler having a filling-engaging point, and a swiper pivotally mounted at one side of said point and adapted to normally engage 75 the filling and be held by the latter against outward swinging to filling-changing position; an extension connected with said swiper and extending to the opposite side of said filling-engaging point, said extension having a portion to frictionally engage the filling to hold said swiper against outward swinging as long as a predetermined quantity of filling remains upon the bobbin. 80

2. In combination with a loom feeler 85 having a filling-engaging point, and a swiper pivotally mounted at one side of said point and adapted to normally engage the filling and be held by the latter against outward swinging to filling-changing position; an arm pivoted to said swiper and extending therefrom to the opposite side of said filling-engaging point, said arm having a portion adapted to engage the filling frictionally to hold the swiper against outward swinging as long as a predetermined amount of filling remains upon the bobbin, 90 said filling-engaging point having a guide through which said arm passes slidably. 95

3. In combination with a loom feeler 100 having a filling-engaging point, and a swiper pivotally mounted at one side of said point and adapted to normally engage the filling and be held by the latter against outward swinging to filling-changing position; an ear secured to and projecting inwardly from said swiper toward said filling-engaging point, the latter having a slot at the inner end of said ear, an arm passing through said slot, and a pivot connecting 105 said arm with said ear, the end of the arm remote from the slot being provided with a shoe to frictionally engage the filling and hold said swiper against outward swinging as long as a predetermined amount of the 110 filling remains upon the bobbin. 115

In testimony whereof I have hereunto affixed my signature.

WILLIAM H. SPENCER.
